CLAIM

The ornamental design for a stackable tray for displaying and dispensing cylindrical packaged articles, as shown and described.

DESCRIPTION

FIG. 1 is a top perspective view of a stackable tray for displaying and dispensing cylindrical packaged articles showing my new design;

FIG. 2 is a top plan view thereof;

FIG. 3 is a left side elevational view thereof, the right side being a mirror image thereof;

FIG. 4 is a rear elevational view thereof;

FIG. 5 is a front elevational view thereof; and

FIG. 6 is a cross-sectional view taken at the line 6—6 of FIG. 5.

*Fig. 1.**Fig. 2.**Fig. 3.**Fig. 4.**Fig. 5.**Fig. 6.*
